UNITED STATES PATENT OFFICE.

CHARLES H. PARSHALL, OF DETROIT, MICHIGAN, ASSIGNOR TO THE MICHIGAN LUBRICATOR COMPANY, OF SAME PLACE.

CRANK-PIN OILER.

SPECIFICATION forming part of Letters Patent No. 296,214, dated April 1, 1884.

Application filed October 17, 1882. Renewed February 21, 1884. (No model.)

To all whom it may concern:

Be it known that I, CHARLES H. PARSHALL, of Detroit, in the county of Wayne and State of Michigan, have invented a new and useful

5 Improvement in Crank-Pin Oilers; and I do declare the following to be a full, clear, and exact description of the same, such as will enable others skilled in the art to which it pertains to make and use it, reference being had to the accompanying drawings, which form a part of this specification.

This invention relates to certain improvements in that class of lubricators which are employed to lubricate crank-pins, and has for 15 its object to provide a novel combination and arrangement of parts whereby the oil is delivered from a reservoir to a transparent chamber located outside thereof, through which the oil passes in visible drops, the transparent 20 chamber being attached to and supporting a neck or tube which connects with flexible tubes for supplying the lubricant to the crank-pin.

The object of my invention I accomplish in 25 the manner illustrated in the accompanying drawings, in which—

Figure 1 is a side elevation of a crank-pin lubricator embodying my invention; and Fig. 2, a modification, which will be hereinafter explained:

In carrying out my invention, A represents any suitable reservoir for the oil.

B is a crank-pin to be oiled.

C is any stationary support.

35 D is a flexible metallic connection between the crank-pin and the reservoir. This flexible connection may be in the nature of a telescopic arrangement of tubes D' and D'', one operating within the other as the crank operates, as 40 shown in the drawings; or, as shown in the variation, the tube may be made in the nature of an elbow-joint which straightens out as the crank recedes and doubles up as it advances.

E is a water-chamber, made of glass or other 45 transparent medium. It is so located outside of the oil-reservoir and between the reservoir and the flexible tubes which connect with the crank-pin that the oil, as it leaves the reservoir, rises through the water in visible drops, 50 thus indicating the rate of feed. Instead of

being a water-chamber, however, this might be a transparent air-chamber and the oil be caused to drop down through it, it only being essential that the chamber should be transparent.

The neck d, which connects the transparent chamber with the flexible metallic connection, may be of any desired length. It may, as shown in the drawings, be such as to locate the reservoir close to the crank; or the reservoir may be located in any other place and the oil be carried thence to the transparent chamber E, and thence to the flexible connection, and so to the crank-pin.

If the device is of the telescopic form shown 65 in the drawings, it will operate more or less in the nature of a pump, and in that event there should be a valve, F, located at the top of the transparent chamber. So also I prefer, generally, to employ a valve, G, for regulating the flow of oil. A lubricator of this character will be found to be very effective in its 70 operation, while the supply of oil is kept uniform and the reservoir is at all times accessible for refilling, cleansing, &c.

75 It is apparent that at the top of the flexible tubes, where they connect with the water-chamber or with the pipe leading therefrom, there is provided a flexible joint, so as to conform to the movement of the crank, and a similar flexible connection is made at the point where it is united to the crank-pin.

Heretofore an oil-reservoir has been connected with a crank-pin through the medium of telescopic tubes, and in another instance a lubricator for steam-cylinder chests has been provided with a transparent chamber through which the oil is fed in visible drops; but, so far as I am aware, a crank-pin oiler has never combined in its structure a stationary oil-reservoir, 85 flexible metallic tubes connecting the reservoir with the crank-pin, and a transparent chamber located between the oil-reservoir and flexible metallic tubes, such combination effecting a new result, and requiring an adaptation or organization of parts for effecting such 90 result.

95 What I claim is—

100 1. A crank-pin lubricator combining in its structure the following elements, to wit: a sta-

- tionary oil-reservoir, a transparent chamber located outside of the reservoir at the side of the same, and connected therewith at one end, and flexible metallic tubes connected with the 5 other end of the transparent chamber by a joint, the said chamber being interposed between the reservoir and the upper portion of the tubes, substantially as and for the purpose described.
2. The combination, substantially as hereinbefore described, of a stationary oil-reservoir, a transparent chamber located outside of but adjacent to the side of the reservoir, and connected at one end with the latter, a neck or

tube attached to and communicating with the other end of the transparent chamber, and 15 flexible metallic tubes connected with the said neck or tube by a joint, the transparent chamber being located between the reservoir and the tubes, substantially as and for the purpose described. 20

In testimony whereof I sign this specification in the presence of two witnesses.

CHARLES H. PARSHALL.
